A. I. JORDAN

MOTH BALL BAG OR CONTAINER

Filed April 13, 1921

FIG. 1.

FIG. 2.

FIG. 3.

FIG. 4.

Inventor
Abraham I Jordan

By his Attorneys

Edgar V. Estes.

UNITED STATES PATENT OFFICE.

ABRAHAM I. JORDAN, OF NEW YORK, N. Y.

MOTH-BALL BAG OR CONTAINER.

Application filed April 13, 1921. Serial No. 460,873.

To all whom it may concern:

Be it known that I, ABRAHAM I. JORDAN, a citizen of the United States, and residing at New York, in the county of Manhattan and 5 State of New York, have invented certain new and useful Improvements in Moth-Ball Bags or Containers, of which the following is a specification, such as will enable those skilled in the art to which it appertains to 10 make and use the same.

This invention relates to what are known as moth ball bags or containers and the object thereof is to provide an improved device of this class which is simple in construction, 15 comparatively inexpensive, and which may be suspended from a hook or other support in a wardrobe, closet or any other place or compartment in which garments or any other articles subject to the ravages of moths 20 are stored or suspended, and with this and other objects in view the invention consists in a device of the class specified, constructed as hereinafter described and claimed.

The invention is fully disclosed in the following specifications of which the accompanying drawing forms a part, and in which—

Fig. 1 is a side view of a bag or other container involving my invention;

30 Fig. 2 a section on the line 2—2 of Fig. 1;

Fig. 3 a view similar to Fig. 2 but showing the bottom portion of the bag or container only, and also showing a modification; and

35 Fig. 4 a section on the line 4—4 of Fig. 3.

My improved moth ball bag or container is shown at *a*, and is shown in the form of a bag the length of which is greater than the depth, but the shape or form of said bag or 40 container may be varied as desired, and the depth may be equal to or greater than the length thereof.

The bag or container is composed of any suitable finely perforated or other open-work material and may be composed of thin sheet metal perforated, or of wire mesh, but I prefer to form it of open-work fibrous material treated so as to give the material a certain degree of rigidity, while rendering it 50 flexible and slightly elastic.

The bag or container consists of a single sheet of material folded centrally as at *a*² to form two side portions *a*³ which are brought together at *a*⁴ to form the top of the bag or container, and the end or side edge 55 portions of the sheet thus folded, as well

as the top edge portions thereof, are stitched together at *a*⁵ to form a closed bag or container, and in this operation said end portions or side edge portions and the top edge portions are also preferably provided with a binding *a*⁶.

The operation of folding the sheet of material as herein described and binding or connecting the end or side edge portions thereof forms at the opposite ends of the bag or container and at the bottom thereof downwardly directed pockets or receptacles *a*⁷, in the form of construction shown, said pockets or receptacles being simple incidents 70 of the method described of forming the bag or container, but the operation referred to may be so carried out as to avoid the formation of the pockets or receptacles *a*⁷.

In one side of the top portion of the bag 75 or container is an aperture *b* which is preferably semi-elliptical in form, and the edges of which are provided with binding *b*², and said aperture is to permit of the insertion of moth balls *c*, any desired number of which 80 may be placed in said bag or container, and instead of moth balls small bodies of other material having the same qualities of the moth balls and of any desired form may be inserted into the bag or container through 85 said aperture. At the back of said aperture and within the bag or container is suspended a shield or door member *b*³ which is adapted to close or partially close the aperture and to prevent the discharge therethrough of the 90 balls *c* in the manipulation of the bag or container after said balls have been passed thereto, and said shield is composed of the same material as the bag or container and is secured between the top edges of the side 95 portions thereof, and in the construction shown, is reinforced at the back thereof by a narrow strip *b*⁴ also secured between the top edges of the side portions of said bag or container.

100 Secured to the top of the bag or container and in any desired way is a flexible strap or hanger *d*, loop shaped in form, and the ends of which may be carried down into the bag or container and form the reinforcement *b*⁴ of the shield *b*³.

I also preferably place in the bottom of the bag or container a reinforcing and strengthening strip or bar *e* made of wood or other fibrous material, and this reinforcing strip or bar is also employed in the construction shown in Fig. 3 which differs from

that shown in Figs. 1 and 2 only in the employment of reinforcing covering *f* for the bottom portion of the bag or container and which is preferably composed of cloth or other fibrous material.

In the use of this device or these devices any desired number thereof may be suspended from a hook, nail or other support in a closet, wardrobe or other compartment containing garments of any kind or any material subject to the ravages of moths or other insects, and one bag or more may be suspended from another by passing the suspending loop member *d* of one through the loop member of another.

My invention is not limited to the exact details of construction and form herein shown and described, nor to any specific material and changes therein and modifications thereof may be made within the scope of the appended claims without departing from the spirit of my invention or sacrificing its advantages.

Having fully described my invention, that which I claim as new and desire to secure by Letters Patent, is:

1. A moth ball container of the class described comprising a bag composed of open-work material, the edges of said bag being bound and the top part of said bag having an aperture through which moth balls may be inserted into the bag, and the bottom of said bag being provided with reinforcing material.

2. A moth ball container of the class described comprising a bag composed of open-work material, the edges of said bag being bound, the top part of said bag having an aperture through which moth balls may be inserted into the bag, and means for reinforcing the bottom portion of the bag.

3. A moth ball container of the class described, substantially of bag formation and composed of openwork material, means for reinforcing and finishing the edges of the material of said bag, means whereby moth balls may be inserted into the bag, and a rod adapted to be placed in and to extend longitudinally of the bag to retain said bag in predetermined shape.

4. A moth ball container of the class described, substantially of bag formation and composed of openwork material, means for reinforcing and finishing the edges of the material of said bag, means whereby moth balls may be inserted into the bag, a rod adapted to be placed in and to extend longitudinally of the bag to retain said bag in predetermined shape, and a shield secured to the bottom portion of the bag.

5. A moth ball container of the class described, substantially of bag formation and composed of openwork material, means for reinforcing and finishing the edges of the material of said bag, means whereby moth balls may be inserted into the bag, a rod adapted to be placed in and to extend longitudinally of the bag to retain said bag in predetermined shape, a shield secured to the bottom portion of the bag, and means centrally of the upper edge of the bag for suspending the same from a suitable support.

In testimony that I claim the foregoing as my invention I have signed my name in presence of the subscribing witnesses this 11th day of April, 1921.

ABRAHAM I. JORDAN.
